July 25, 1882

No. 13,083

UNITED STATES PATENT OFFICE.

JOHN GLEN, OF BROOKLYN, NEW YORK.

DESIGN FOR A PRINTED FABRIC.

SPECIFICATION forming part of Design No. 13,083, dated July 25, 1882.

Application filed May 18, 1882. Term of patent 3½ years.

To all whom it may concern:

Be it known that I, JOHN GLEN, of Brooklyn, Kings county, in the State of New York, have invented a new and original Design for Printed Fabrics; and I do hereby declare that the following specification, taken in connection with the accompanying illustration, forming a part of the same, is a full, clear, and exact description thereof.

10 My design relates particularly to printed fabrics known as "calicoes," although it is equally applicable to silks, woolens, and other fabrics, either printed or woven.

15 It consists in the representation of hanging baskets of flowers, birds, and insects, as will hereinafter appear.

20 Referring to the illustration, A represents a basket of flowers supported by a butterfly, B. Other butterflies, B', and birds C C', appear upon the ground of the fabric, and immediately above the hanging baskets of flowers are ar-

ranged sprays of flowers D, although the said sprays may be omitted, if desired. The component parts of the design are repeated upon the surface of the fabric to form the pattern. 25

The fabric may be produced in any preferred variety or combination of colors for giving a desirable effect to the design.

What I claim, and desire to secure by Letters Patent, is— 30

1. The design for printed and other fabrics, consisting of baskets of flowers, birds, and butterflies, substantially as set forth.

2. The design for printed and other fabrics, consisting of baskets of flowers, birds, butterflies, and sprays of flowers, substantially as described and shown. 35

JOHN GLEN.

Witnesses:
